OF ALPINE, ARIZONA

OIL FILTERING AND REFINING MEANS

Application filed July 1, 1930. Serial No. 375,286.

This invention refers to an oil filtering and refining means for automobiles.

The principal object of this invention is to produce a device which may be utilized on any standard automobile or in combination with an engine for the purpose of refining the oil used therein.

Another object is to produce a device of this character wherein the filtering and refining element may be quickly removed and replaced with a new element.

A further object is to produce means whereby the filtering element will be automatically removed from the flow of fluid should for any reason the element become clogged, thereby permitting the oil to by-pass the element.

A still further object is to provide a device which is neat in appearance and economical to manufacture.

Other objects and advantages will be apparent during the course of the following description.

In the accompanying drawings forming a part of this specification, and in which like numerals are employed to designate like parts throughout the same,

Figure I is a vertical cross-section of my device, and

Figure II is a side elevation of the filtering and refining element.

At the present time it is common to employ filters of this character in connection with automobiles. These filters do not in any sense of the word refine the oil passing there-through, they merely strain out particles of sediment in the oil. Applicant's device differs in that he not only strains the oil but he also employs a refining medium which has an affinity for oil, and will absorb five times its own weight in the lighter oil products such as gasoline, naphtha and the like which has diluted the oil being filtered.

It is also a common fact that with the present type of filter, as soon as the filter becomes clogged a by-pass is permitted which is supposed to prevent the continuous flow of the fluid around the filtering element. The arrangement is such, however, that the by-pass often becomes stuck with the result that the

pressure within the device will break the container and the oil will be lost.

In my device this is impossible due to the simplicity of construction and further my device is so constructed that it is impossible for any of the fluid within the device to return to the engine when the same stops, while in the present form of device the oil within the strainer will gradually siphon back into the crankcase and draw the sediment or sludge contained within the filtering element, thus undoing all of the work of the filter.

In the accompanying drawings wherein for the purpose of illustration is shown a preferred embodiment of my invention the numeral 5 designates the case of my device having a bottom 6 and a top 7. The bottom and top are both removable from the case 5. However, in use the top is the only part that is easily removed, which is accomplished through the medium of a boss 8 to which a wrench may be applied.

An inlet pipe is shown at 9 which has a tapered extremity 11. An outlet pipe is shown at 12. The construction thus far describes my device as far as the same is permanently attached to the vehicle. The filtering and refining element is housed within this device and consists of a cylindrical cartridge which is preferably formed of two layers of wire mesh in the form of cylinders 13 and 14 concentrically arranged and between which is a cloth fabric 16.

The inner wire mesh 14 serves to support a plastic refining medium 17. This medium is pasted or otherwise placed on the mesh, while the top plate 18 and the bottom plate 19 are provided with annular substantially channel shaped recesses arranged at the outer peripheries thereof and provides seats for the ends of the wire mesh cylinders and cloth fabric 16, the walls of the recesses being curved and crimped upon the cylindrical mesh construction.

The cap 18 has a dome 21 formed therein the purpose of which will be later seen.

The bottom 19 has a conical upset 22 to which a pipe 23 is connected. The upper end of the pipe is serrated and projects into the dome 21. A spring 24 rests upon the cap 18.

and against the cover 7. The result of this construction is that when oil enters as shown by the arrow in Figure I, the oil will pass upwardly through the pipe 23 into the dome 21, and will fill the refining element passing through the filtering material, and screens thence into the space between the element and the case 5 to be discharged through the pipe 12.

Should for any reason the filtering and refining element become clogged, the pressure of oil therein would quickly overcome the spring 24 and raise the entire element away from the tapered end 11 with the result that the filtering and refining element would move into the dotted line position of Figure I, and then the oil would flow directly from the pipe 9 to the space between the filtering element and the case 5, as shown by the dotted arrow of this figure. When it is desired to renew the filtering element the cap 7 is unscrewed, and the element lifted out, and due to the fact that the pipe 23 extends to the top of the filtering element and into the dome 21, it is apparent that none of the dirty oil contained within the filtering element can run back into the clean oil, or into the crankcase. This same fact is true when the engine stops running in that it is impossible for the oil within the filter to return to the crankcase as the only amount of oil that can be sucked back is that small portion within the dome 21 which is negligible.

It will thus be seen that I have provided a very simple device which will perform all of the objects herein set forth.

It is to be understood that the form of my invention herewith shown and described, is to be taken as a preferred example of the same and that various changes relative to the shape, size, material and arrangement of parts may be resorted to without departing from the spirit of the invention, or the scope of the subjoined claim.

Having thus described my invention, I claim:—

In an oil filtering and refining device, a case, a bottom and a top for said case and detachably secured with respect thereto, an inlet pipe extending centrally through the bottom and terminating above said bottom in tapered formation, an outlet pipe extending laterally from said case, a filtering element including a cap, a dome centrally formed with said cap, a bottom having a raised conical portion disposed for fitting engagement with the tapered upper end of said inlet pipe, a pipe formed with and rising from the raised conical portion and being provided with a serrated upper end projecting to the dome, said cap and bottom of the filtering element being provided with annular substantially channel shaped recesses arranged at the outer perforations thereof, concentrically arranged cylindrical screen members surrounding the

serrated pipe and having their ends secured in the recesses, a fabric element between the screen members, resilient means for urging the conical portion in engagement with the inlet pipe so that the latter is in registration with the serrated pipe, and a plastic refining medium applied to the innermost screen member and arranged therein.

In testimony whereof I affix my signature.

LEE HARVEY.
